S. H. Ransom, Albany, N. Y. - Letters Patent
No. 225, dated June 26, 1849.

The Schedule referred to in these Letters Patent and making part of the same.

Be it known, that I Samuel H. Ransom of the City of Albany and State of New York, have produced a new ornamental design for an air tight parlour stove, and I do hereby declare, that the annexed drawing is a full and accurate delineation of a stove constructed after my design: the side and back plates not shown by the drawing being similar to and symmetrical with the side and front plates represented on the drawing - except that the Back plate has the usual opening and flange, for the applying and fitting, of the pipe or smoke flue to the stove.

What I claim as my invention and desire to secure by Letters Patent is the combination and arrangement of ornamental figures and forms represented in the annexed drawings making an ornamental design for an air-tight parlour stove.
